UNITED STATES PATENT OFFICE.

RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOEMAKING-MACHINE.

1,169,201.

Specification of Letters Patent. Patented Jan. 25, 1916.

Application filed March 25, 1912. Serial No. 686,042.

To all whom it may concern:

Be it known that I, RALPH C. SIMMONS, a citizen of the United States, residing at Beverly, in the county of Essex and State of Massachusetts, have invented certain Improvements in Shoemaking-Machines, of which the following description, in connection with the accompanying drawings, is a specification, like reference characters on the drawings indicating like parts in the several figures.

This invention relates to shoe making machines and is herein shown and described, by way of exemplification merely, as embodied in a machine for breasting heels. It is to be understood, however, that various features of the invention are susceptible of embodiment in other machines.

It is usual, in finishing the heels of certain styles of shoes, to breast the heels of a pair with the edges of the heel breasts equally and oppositely inclined to the longitudinal median lines of the heels. Difficulty has been experienced, however, in accurately positioning and holding the heels for this operation, and it is an object of the present invention to provide means for enabling a shoe to be positioned accurately and held positively which engages and moves with the forepart of a shoe, and also to provide new and improved means for locating and holding the heel portion of a shoe against movement in the plane of a tread face.

An important feature of the invention consists in a forepart engaging and positioning device having inclined forepart engaging faces acting automatically to position the shoe relatively to the knife irrespectively of the size of the shoe and is herein shown as arranged to move with the shoe equal and opposite distances from a normal position in which the longitudinal median line of the shoe is perpendicular to the plane of the knife to position the shoe relatively to the knife for breasting heels rights and lefts. In the form shown, the toe portion, or the forepart, of the shoe is engaged by a V-shaped notch in a locating plate which acts to center the shoe over the apex of the notch irrespectively of width or size of the shoe. In order to provide for the right and left positioning movements of the toe portion of a shoe, the locating plate is arranged for limited sliding movement in

a horizontal plane, means being provided for adjustably limiting this movement.

Another feature of the invention consists in a locating plate mounted for movement vertically and normally held in an elevated position by resilient means. This construction enables the shoe to be located laterally while it is still free to be moved in a vertical plane, so that the tread face of the heel may be brought into parallelism with the tread or presser plate when it is inclined to the horizontal in order to give the breast face an oblique inclination to the tread face of the heel.

It is found in practice that there is considerable variation in the height, from toe to heel seat face, of commercial lasts which are normally of the same size and hence it is found that for a given vertical adjustment of the last pin of the jack there will be considerable variation in the distance between the presser plate and the tread face of the heel, and hence a back stop on the presser plate which will engage the rear of the top lift of one heel may fail to engage, because of variation in the height of the last, another heel of what is really a shoe of the same size and style.

Accordingly another feature of the invention consists in a back stop which automatically accommodates itself to height variations of lasts and engages the shoe at the rear and positions it relatively to the knife irrespectively of any ordinary height variations. This stop comprises a member pivotally connected beneath the presser plate at some distance to the rear of the heel. The forward end has a limited free movement vertically and is held in its lowermost position by gravity. The forward portion of the stop is upwardly inclined and is arranged to be engaged by the upper edge of a rearwardly moving heel and moved upwardly about its pivot until the rear face of the heel comes in contact with a projection carried upon the inclined face of the stop member, whereupon the rearward movement of the heel is terminated and the longitudinal position of the heel relatively to the knife determined. As the presser plate is now depressed to clamp the heel, the stop member, by reason of its pivotal connection with the presser plate, maintains its operative position against the heel.

Another feature of the invention comprises novel mechanism for holding the heel portion of the shoe from movement in the plane of the tread face of the heel. This mechanism comprises means resiliently pressed inwardly to engage the heel upon opposite sides and means whereby the heel engaging means are automatically locked in place as the shoe is positioned relatively to the knife and act to hold the heel firmly in place until the breasting operation is completed, whereupon as the shoe is withdrawn from beneath the knife the locking means is released and the side engaging means are free to position themselves against a new heel, irrespectively of its width. As herein shown the side engaging means comprises members which are carried upon arms connected together for equal and opposite movement, and a spring is provided for holding them in an initial position such that the distance between them is less than the width of the kind of heel being breasted. Means is provided also for varying the initial distance between the members for different sizes of heels. Means is also provided for positively locking the arms when they have assumed their position against the sides of the heel, and as herein shown this means is operated by pressure against the stop member which engages the rear face of the heel. As the heel is pushed into place the clamping members are separated and the heel permitted to engage the back stop and the rearward and lateral position of the heel is determined. By a slight further pressure against the back stop the locking mechanism is operated which positively holds the clamping members against the sides of the heel until after the breasting operation, when a slight movement of the shoe longitudinally forward releases the locking mechanism which remains inoperative until another shoe is introduced.

Another feature of the invention consists in means for positioning and clamping the shoe which is mounted independently of the presser plate which engages the tread face of the heel for movement in the plane of the tread face about an axis which lies at the mid portion of the front edge of the presser plate and substantially perpendicular thereto. This construction permits the shoe to be swung after it is clamped about the said axis which approximately coincides with that of the heel pin of the last so as to locate the heel for breasting rights and lefts. Means is provided for limiting the movement of the shoe positioning and clamping means equally in opposite directions or the amount of lateral swing of the shoe may be determined by movements of the toe rest, as has been described.

These and other features of the invention, including novel means for taking up wear

in the knife actuating and controlling mechanism and for preventing slipping of the heel, and certain more important details of construction and combinations of parts will now be described in connection with the drawings and then pointed out in the claims.

In the drawings,—Figure 1 is a perspective view of portions of a breasting machine provided with an illustrative embodiment of certain features of my invention including the novel toe rest and forepart locating device; Fig. 2 is a plan view of the heel clamping and positioning mechanism detached from the machine; Fig. 3 is a longitudinal section on the line 3—3 of Fig. 2; Fig. 4 is a perspective view of the presser tread plate and adjacent parts; Fig. 5 is a side view of a detail; Fig. 6 is a sectional detail.

The machine frame is designated, Fig. 1, by the numeral 2 and is provided with grooves or ways 4 in which the knife carrying slide 6 and the knife actuating slide 8 are mounted for vertical reciprocation. The latter is power actuated through a suitable one-revolution clutch which is tripped by the last part of the downward stroke of the treadle of the machine. A slide 10 carrying a heel support comprising a tread or presser plate 12 is depressed upon the heel by the first part of said treadle stroke. The knife carrying slide 6 has an arm 14 and cheek pieces 16, 18 which form abutments for the ends of the front clamping plate 20 for the knife 22. The knife is clamped in its holder by screws 24 and is adjusted longitudinally by the abutment screws 26.

The knife carrier slide 6 is detachably connected with its actuating slide through a strut 45, Fig. 6, pivoted to carrier 6 at 42 and engaging under a roll 47 on the slide 8. The strut is engaged by the upper arm 44 of a bell crank which is also pivoted at 42 to the knife carrier and the horizontal arm 40 of which carries adjustably a shank gage or stop 50 which, upon meeting the shank of the shoe, forces strut 45 from under roll 47 and allows the roll and the knife actuating slide 8 to proceed to the completion of their down stroke without further actuating the knife. On its upward stroke the actuating slide picks up the knife carrier to lift the knife by meeting a cap plate 30, Fig. 1, that is fastened to the top of the knife carrier and overlies the actuating slide. A spring 41, Fig. 6, is provided to press the strut 45 under the roll 47 when the slide has picked up the carrier. Lost motion or wear sometimes makes adjustment necessary in order that the strut and roll may properly reengage and this is provided by forming on the lower face of the cap plate 30 a rib 32 and fastening the plate to the knife carrier by screws 34 located on opposite sides

of the rib whereby the plate can be tipped about the rib to adjust up or down the edge portion which is engaged by the actuating slide. A vertical adjusting screw stop 46 depending from arm 40 of the bell crank and engaging the knife carrier 6 variably determines the extent to which the strut 45 shall extend under the roll 47 and thus variably determines the further movement of the knife which shall occur after the shank gage 50 meets the work and before the knife is freed from its actuator.

The shoe is supported upon a jack comprising the usual rigid support for the heel end of the last comprising a last pin 60 on a post 61 and a toe rest comprising an arm 62 which branches from the post and carries the novel toe rest and toe locating device embodying an important feature of my invention. This comprises a vertically movable slide 64 having dove-tailed guides connecting it with a member 66 and normally held elevated by a spring 68. The member 66 is mounted for lateral sliding movement upon a bar 70 which is fixed to a standard 72, the standard being mounted for vertical adjustment in the block 76 by the worm 74. The block 76 is adjustably fastened to a plate 82 by the thumb screw 78 and slot 80 in the plate 82. Adjustment of the toe rest as a whole upon the arm 62 is provided by another slot in the plate 82 and the set screw 84 passing through that slot and threaded into the arm 62. To limit the lateral sliding movement of the toe rest upon the bar 70, stop screws 65, 67 are provided which are threaded through the member 66 and are arranged to contact with the standard 72 and limit the movement of the member 66 on the bar 70 and hence the movement of the toe resting and locating plate 64. Spline and groove connections are provided between the bar 70 and the member 66 and between the standard 72 and the block 76 to prevent relative rotary movement of the parts. When there is no shoe on the jack the plate 64 will be elevated by the spring 68 and when the shoe is placed on the heel pin 60 with the toe resting upon the plate 64 it will be depressed more or less. The shoe may be swung either to right or left until one or the other of the stop screws 65, 67 strikes the post 72. The right or left swing of the shoe is thus determined and hence the inclination of the plane of the knife or heel breast to the longitudinal median line of the heel. The V-shaped notch in the plate 64 centers the shoe over the member 66 irrespectively of its width or size and the amount of lateral swinging movement of the shoe may be changed or adjusted by the screws 65, 67. When the heel is clamped by the tread plate the forepart will be raised or lowered automatically to bring the tread face of the heel into parallelism with the acting face of the plate and determine the vertical inclination on which the heel will be breasted. The spring 68 allows the forepart rest to yield to or to follow up the movement of the forepart of the shoe 70 while continuing to control the lateral position of the forepart.

The tread plate 12 is adjustably secured to a casting 90 by screws 92. The casting 90 is pivoted at 94 to the slide 10 and the usual means, comprising a screw 93 acting against an upward extension 95 of the casting 90, is provided for adjusting the tread plate angularly about the pivot 94 for varying the inclination of the breast to the tread face of the heel. The extension 95 and screw 93 are maintained in engagement by the weight of the parts, as the weight of the parts to the rear of the pivot pin 94 is in excess of that in front. A segmental T slot 96 is formed in the casting 90 which receives a T guide 98 on a plate 100. The parts 90 and 100 have their relative movement properly limited for a purpose to be described by pins 102 which engage any one of a series of holes in the part 100 and abut against the part 90. On its under side the plate 100 is provided with guides 106, Fig. 3, in which a plate 108 is mounted for adjustment longitudinally of the shoe. To 95 the plate 108 is pivoted at 110 a member 112 having an upwardly projecting forward portion 111 provided with a vertical stop face 113, with which the rear edge of the shoe heel may contact. The inclined portion 111 extends upwardly through a slot in the tread plate 12, Fig. 4. When there is no shoe in the machine the member 112 drops down as far as the projection 114 thereon, Fig. 3, will permit, the end of the 100 portion 111 being then only slightly above the lower face of the tread plate 12. As the shoe is swung in under the tread plate it will engage the inclined face of portion 111, whether the particular last brings the 105 shoe up close to the plate 12 or not, and as the shoe is pushed backwardly it will act on the inclined portion 111 to raise the member 112 and will finally contact with the stop 113, its rearward movement being thus 110 arrested. For adjusting the plate 108 and hence the member 112 and stop 113 forwardly and backwardly, in accordance with the size of the heel and the amount to be removed therefrom by the breasting operation, one edge of the plate 108 is provided with teeth, Fig. 2, which engage a worm 116 which is adapted to be turned by hand for adjusting the plate and consequently the stop 113 backwardly and forwardly. The 115 tread or presser plate 12 is slightly hollowed out or concave on its under face so that more pressure is applied to the heel about its periphery than upon its central portion, whereby lateral and swinging 120

movements of the shoe relatively to the plate are prevented. As rearward movements of the shoe are controlled by the back stop 113, the concavity of the presser plate is preferably transverse or cylindrical with the axis of the cylindrical concavity extending longitudinally of the shoe.

For positioning and holding the heel laterally, arms 130, 132 are provided which are pivoted at 131, 133, respectively to the plate 100 and are curved away from each other so as to contact at their ends only with the sides of the heel, the ends being formed with cylindrical enlargements 129 which permit lateral swinging of the shoe on the toe rest but hold the heel against lateral bodily movement. The arms 130, 132 have inwardly extending portions 134 formed with meshing teeth so that their shoe engaging ends will move equally and oppositely and the arm 130 has a rearward extension 136 carrying a toothed segment which meshes with a toothed portion of a cross bar 138. The bar 138 is mounted for sliding movement in depending portions of the plate 100 below the plate 108 and is held in place by a retaining plate 140, Fig. 1. The cross bar 138 is normally forced to the right by a helical expansion spring 142 which is positioned on studs 139 and 101 secured to the bar 138 and the plate 100, respectively. The spring 142 obviously holds the shoe engaging ends of the arms 130, 132 toward each other or closed upon the shoe and the normal separation of the arms is controlled by a stop pin 141 adapted to engage any one of a series of holes 143 in the left-hand end of the bar 138 and arranged to contact with the part 100. As the shoe is swung in beneath the plate the arms 130, 132 center the heel laterally and are separated by introduction of the heel between them and then the rear edge of the heel engages the inclined portion 111 of the member 112 and is arrested by contact with the stop 113.

It is desirable to have the arms 130, 132 locked against separation when the shoe is fully positioned and this is effected by a slight rearward movement of the stop 113 by pressure of the shoe against it. The worm 116 is fixed to a stem 150 which slides in a lug 152 on the part 100 and passes through a hole in that part, Fig. 5, into engagement with a catch lever 154 pivoted at 156 between its ends and having its lower end formed to interlock with notches 158 in the rear edge of the bar 138, Fig. 2. The catch lever is normally held out of engagement with the notches in the bar 138 by a spring 160, which, acting through the lever 154, the stem 150, the worm 116 and the plate 108, holds the back stop 113 in forward position. Conversely, pressure of the shoe upon the back stop 113 acts through

this same chain of mechanism to place the spring 160 under greater tension and force the catch 154 into engagement with the teeth 158 in the bar 138, thus locking it against longitudinal movement and holding the arms 130, 132 in engagement with the shoe.

It will be observed that the whole heel positioning and clamping mechanism except the tread plate 12 is mounted on the plate 100 which is formed with the T-shaped segmental rib 98 mounted for sliding movement in the part 90 as described and that after the shoe is positioned by the back stop and its heel clamped by the side arms it may be swung with these clamping means and the plate 100 about the center of curvature of the guide rib 98 (which lies approximately at the edge of the tread plate) to the right or left to an extent limited by the position of the pins 102 in the holes 103 in the opposite ends of the rib 98. Means is thus provided for positioning the heels of right and left shoes, which positioning means may be used in conjunction with the toe resting and locating device or independently thereof.

In the operation of the machine the jack is swung forward in the usual manner and the shoe, with the last in it, placed upon the pin 60, or, alternatively, for breasting off the last, a heel plate might replace the last pin 60, with the toe in the notch of the plate 64 which centers the forepart of the shoe and permits movement thereof vertically to accommodate it to the inclination of the plate 12. The jack is then adjusted vertically by the usual hand wheel, Fig. 1, to the approximate height appropriate for the size of the shoe that is to be breasted. The shoe is next swung back with the jack beneath the plate 12 and between the side engaging ends 129 of the arms 130, 132 which center the heel and then separate against the tension of the spring 142 and move the bar 138 outwardly. The rear edge of the shoe heel engages the inclined portion 111 of the back stop 112 and raises it until the shoe contacts with the stop 113 against which it is pushed with sufficient pressure to overcome the tension of the spring 160 and force the locking catch 154 into engagement with the notches 158 on the bar 138 to lock it and the said engaging members 129 against movement. The tread plate is then partially depressed by the starting treadle and the shoe swung to the right or left, according to whether it is a right or left shoe, until one or the other of the screws 65, 67 engages the standard 72 or one or the other of the pins 102 engages the part 90, if the pins are employed. The treadle is then further depressed to apply more pressure to the tread face of the heel to clamp it firmly and to trip the clutch whereupon the actuator

slide 8 will descend carrying with it the knife slide 6 and knife 22 until the latter is about to reach the shank when the stop 50 will come in contact with the shank and tip 5 the lever 40 about the pivot 42 until the upper end of the arm 44 pushes the strut 45 from beneath the roll 47 on the actuator slide 8. The knife is thus disconnected from its actuating mechanism and ceases to cut by 10 the time it has passed through the heel. The actuator then completes its stroke and upon its return comes in contact with the plate 30 and lifts the knife to its initial position, allowing the arm 44 to resume its 15 normal position and the strut 45 to become reseated under the roll for the succeeding operation.

Claims to the work support *per se* will be presented in a separate divisional application.

Having described my invention, what I claim as new and desire to secure by Letters Patent of the United States is:—

1. A heel breasting machine having, in combination, a breasting knife and shoe positioning means comprising a heel support and a forepart rest adapted to engage the shoe externally and formed with inclined shoe engaging faces to center the shoe automatically on it, said rest being supported for limited movement laterally in either direction to position right and left shoes relatively to the knife for the heels on each to be breasted at equal but opposite angles to 35 the median line of the heel.

2. A heel breasting machine having, in combination, a breasting knife and shoe positioning means comprising a heel support, means connected with the support for positioning the heel laterally relatively to the knife, a forepart rest engaging externally the forepart of the shoe and having provision for positioning the shoe toe laterally, sustaining means on which said rest is laterally movable, and means for adjustably limiting such lateral movement in either direction.

3. A heel breasting machine having, in combination, a breasting knife and shoe positioning means comprising a last support, means engaging the sides of the heel for positioning the heel laterally relatively to the knife, said means being mounted for angular movement with the shoe laterally about a center located in the heel part of the shoe, and means for adjustably limiting such lateral angular movement in either direction.

4. A machine having, in combination, means for operating upon the heel portion of a shoe and shoe positioning means comprising a heel support and a rest engaging the exterior of the forepart and formed with inclined forepart engaging faces to center the forepart laterally on the rest and mov-

able laterally with the forepart relatively to the heel support to change the angular relation of the median line of the shoe to said operating means, and adjustable means for limiting said lateral movement in each 70 direction.

5. A machine having, in combination, means for operating upon the heels of shoes, including a heel tread plate, and shoe supporting means comprising a last support 75 and a forepart rest which is independently yielding to maintain contact with the forepart during movement to bring the heel tread into parallelism with the face of the tread plate.

6. A machine having, in combination, means for operating upon the heels of shoes, including a heel tread plate, and shoe supporting means comprising a last support and a forepart rest which has provision for 85 positioning the forepart laterally and is independently yielding vertically to maintain control of the lateral position of the forepart during vertical movement thereof while the heel tread is brought into parallelism 90 with the acting face of the tread plate.

7. A heel breasting machine having, in combination, a breasting knife, a heel tread plate which positions the shoe relatively to the knife to determine the vertical slant of 95 the heel breast produced by the knife, a last support, and a forepart rest adapted to control the lateral position of the forepart for determining the transverse inclination of the heel breast produced by the knife, said rest 100 being independently yielding vertically to follow up the forepart in the movements incident to the positioning effected by the tread plate.

8. A machine of the class described having, in combination, a knife, and a toe locating device arranged for movement with and by the shoe to permit the toe to be tilted to locate the shoe in angular relation to the tool in a vertical plane and to permit uniform lateral movement of the forepart of the shoe, irrespectively of the size of the shoe for determining the inclination of the longitudinal median line of the shoe to the knife.

9. A machine of the class described having, in combination, a knife, means for actuating the same, a shoe support comprising a rigid last supporting portion and a toe locating member mounted for lateral sliding movement relatively to the heel portion, and means for adjustably limiting said movement for positioning the shoe for breasting heels rights and lefts.

10. In a heel breasting machine, a presser 125 plate for engaging the tread face of a heel, means for varying the inclination of said plate, and a toe rest mounted for vertical movement and resiliently held against the exterior of the toe portion of a shoe.

11. In a machine of the class described, a back stop having a forwardly and upwardly inclined face and an abutment face to engage the top lift of a heel and adapted to be moved vertically by contact of the heel with said inclined face. 5
12. In a machine of the class described, a back stop having a portion to engage the rear part of the heel and to arrest movement 10 of the same in the plane of the tread face of the heel and having a forwardly and upwardly projecting portion with which the heel first contacts and by which the stop and heel are moved relatively until the arresting 15 portion is reached.
13. A machine of the class described having, in combination, a presser plate, and a top lift back stop mounted beneath the same for vertical movement and having a stop 20 face and a forwardly inclined portion with which the heel engages and by which the stop face is moved upwardly to meet the rear edge of the top lift irrespectively of the vertical position of the tread face of the 25 heel beneath the presser plate.
14. A machine of the class described having, in combination, a reciprocating knife and a shoe support comprising a last pin, and a centering and locating device adapted 30 to engage and move with the forepart of a shoe and hold it against lateral movement relatively to said device, said device being supported to permit sliding movement of the device bodily to bring the median line 35 of shoe heels into equal and opposite angular relations to the plane of the knife.
15. A machine of the class described having, in combination, a knife, means for actuating the same, and a shoe support comprising 40 a rigid heel supporting portion and a toe locating member mounted for lateral right line movement to position the shoe with the longitudinal median line of the heel at equal and opposite angles to the 45 plane of the knife irrespectively of the width of the forepart of the shoe.
16. A machine of the class described having, in combination, a knife, means for actuating the same, a shoe support comprising a 50 rigid heel supporting portion, a toe locating member adapted to engage the exterior of the forepart and mounted for lateral right line movement with and by the shoe, and stops for arresting the member with the longitudinal median line of the shoe heel at 55 equal and opposite angles to the plane of the knife.
17. In a heel breasting machine, a presser plate for engaging the tread face of the heel, 60 means for varying the inclination of said plate, and a toe locating device resiliently upheld and adapted to be depressed by contact therewith of the work to permit the said face of the heel to rest squarely against said 65 plate.
18. In a heel breasting machine, the combination of a tread plate, a heel pin, a rest for engaging the toe externally, a member in which said rest is guided for vertical movement, means for guiding said member 70 for horizontal movement, and means for limiting the movement of said member in both directions.
19. A machine of the class described having, in combination, a back stop having a 75 downwardly and rearwardly inclined shoe engaging face, a projection on said face, and means permitting vertical movement of said face upon contact of the heel therewith to permit the shoe to engage the projection. 80
20. In a machine of the class described, a back stop arranged to engage and arrest rearward movement of heels which occupy different vertical positions, and heel engaging means for adjusting said stop vertically 85 in accordance with the position of the heel, said adjustment being effected automatically by the rearward movement of the heel.
21. In a machine of the class described, a presser plate, a back stop arranged normally 90 in definite vertical relation to said plate, and means operated upon introduction of the shoe for varying the vertical position of said stop relatively to the plate in accordance with the vertical position of the heel. 95
22. In a machine of the class described, a back stop, a tread plate having a normal position above the highest heel being breasted, a jack for supporting a shoe and guiding it beneath said plate, and means for engaging the rear top edge of a heel irrespectively of its height and guiding said stop into engagement with said rear edge of the heel 100 to arrest further movement of the heel.
23. A machine of the class described having, in combination, clamping members mounted for equal and opposite movement laterally of a shoe, resilient means for moving said members toward each other, and means adapted to be engaged by the shoe 105 heel when introduced between said members and to be moved by the shoe relatively to said members to effect locking of said members from further separation.
24. A heel breasting machine having, in 115 combination, a knife slide and an actuating slide, means on the actuating slide arranged to engage a member on the knife slide to actuate said knife slide downwardly, and means on the knife slide to be engaged by 120 the actuating slide for raising the knife, said means comprising a plate mounted on said knife slide and projecting into the path of the actuating slide, and means for adjustably rocking the plate for varying the 125 vertical position of the projecting end of said plate.
25. In a heel breasting machine, the combination with a knife slide, an actuating slide carrying a roll, a strut on said knife 130

slide, and a lever arranged to engage said strut which engages the roll on the actuating slide, of means for adjusting the position of the lever and strut relatively to said roll for varying the distance the lever must be moved before it will be disengaged from the roll.

26. A machine of the class described having, in combination, a tread plate, and shoe 10 positioning and holding means arranged beneath said plate and connected thereto for movement relatively to the plate about a vertical axis located adjacent the front edge of the tread plate.

15 27. A machine of the class described having, in combination, a heel tread plate, shoe positioning and holding means adapted to engage the sides of a heel arranged below said plate and connected for movement 20 relatively thereto to the right or left about a center adjacent the front edge of the plate, and means for limiting said movement in both directions.

28. A machine of the class described having, in combination, a tread plate, shoe 25 positioning means adapted to engage the sides of the heel arranged below said plate and movable with the shoe relatively thereto as the shoe is swung for breasting the 30 heel right or left, a toe rest mounted for

lateral movement, and means for limiting the right or left movement of the shoe relatively to the tread plate.

29. A heel breasting machine having, in combination, a knife, a tread presser plate 35 formed to present a transverse concavity upon its under face for preventing lateral movement of the heel, and a back stop arranged to engage the rear face of the heel 40 for limiting rearward movement of the shoe. 40

30. A machine of the class described having, in combination, shoe treating means, a work support movable into and out of position for treatment of the work by said means, work clamping means arranged for equal and opposite movement yieldingly toward and from the sides of the work, a locking bar connected for movement by said clamping means, a stop for engaging the rear face of the work, and means, comprising 45 a lever, connected with said stop for locking said bar against movement when the work is pressed against the stop. 50

In testimony whereof I have signed my name to this specification in the presence of 55 two subscribing witnesses.

RALPH C. SIMMONS.

Witnesses:

CHESTER E. ROGERS,

LAURA M. GOODRIDGE.

Copies of this patent may be obtained for five cents each, by addressing the "Commissioner of Patents, Washington, D. C."

It is hereby certified that in Letters Patent No. 1,169,201, granted January 25, 1916, upon the application of Ralph C. Simmons, of Beverly, Massachusetts, for an improvement in "Shoemaking-Machines," an error appears in the printed specification requiring correction as follows: Page 1, line 72, for the word "normally" read *nominally*; and that the said Letters Patent should be read with this correction therein that the same may conform to the record of the case in the Patent Office.

Signed and sealed this 25th day of April, A. D., 1916.

[SEAL.]

Cl. 12—47.

J. T. NEWTON,

Acting Commissioner of Patents.
